UNITED STATES PATENT OFFICE

104,127

DESIGN FOR A HOLLOW GLASS BUILDING BLOCK

Willard P. Zimmerman, Muncie, Ind., assignor to
Owens-Illinois Glass Company, Toledo, Ohio,
a corporation of Ohio

Application January 31, 1936, Serial No. 60,924

Term of patent 14 years

To all whom it may concern:

Be it known that I, Willard P. Zimmerman, a citizen of the United States, and residing at Muncie, in the county of Delaware and State of Indiana, have invented a new, original, and ornamental Design for a Hollow Glass Building Block, of which the following is a specification, reference being had to the accompanying drawing forming a part thereof.

In the drawing:

Fig. 1 is a perspective view of a hollow glass building block showing my design and bringing out that it consists of ribs extending in opposite

directions on the inner and outer faces of the adjacent wall.

Fig. 2 is a view from the opposite side showing a reversal of the application of the ribs.

Fig. 3 is a sectional view of the block along the line 3—3 of Fig. 2 intended to further emphasize the rib arrangement involved in producing my design.

I claim:

The ornamental design for a hollow glass building block substantially as shown and described.

WILLARD P. ZIMMERMAN.
